INVENTOR.

*John J. Flynn,
By Horatio E. Bellone*

ATTORNEY.

UNITED STATES PATENT OFFICE.

JOHN J. FLYNN, OF PROVIDENCE, RHODE ISLAND.

CHASER.

1,350,862.

Specification of Letters Patent. Patented Aug. 24, 1920.

Application filed October 25, 1919. Serial No. 333,347.

To all whom it may concern:

Be it known that I, JOHN J. FLYNN, a citizen of the United States, residing at Providence, in the county of Providence and 5 State of Rhode Island, have invented certain new and useful Improvements in Chasers, of which the following is a specification.

My invention relates to chasers for use in threading tools and particularly in that type 10 of tools wherein the yielding chaser, embraced by a spring collar, is impelled against the work by a cam collar engaging a cam face on the chaser, and is released from the work by the escape of a flange on the chaser 15 from engagement with the collar. A threading tool of this type is shown in my prior U. S. Patent No. 1,259,504 issued March 19, 1918.

In chasers of this type repeated regrinding of the teeth gradually forms a throat 20 cut of such excessive length upon the lower extremity of the front end face, as to render the chaser useless for work of certain kinds. The essential object of my invention is to 25 enable the chaser to still be utilized as well as originally, and prolong its period of utility.

My invention consists, therefore, in the 30 means for producing the results above specified substantially as hereinafter described and claimed, and as shown in the accompanying drawings, which constitute a part of this invention, wherein—

Figures 1 and 2 are front and back end 35 elevations respectively of my novel chaser,

Fig. 3, a side elevation of the same, and

Figs. 4 and 5, top and bottom plan views respectively of the same.

Like characters of reference indicate like 40 parts throughout the views.

In detail the chaser comprises an oblong body 7 having its front and rear surfaces, 8 and 9, in parallel planes. The lower end of the body is, in this instance, laterally retracted forming a ridge 10 extending the 45 width of the body provided throughout its length with a series of transversely disposed cutting teeth 11. The number of ridges 10 are immaterial. Upon the top end of the

body midway its end surfaces there is a 50 transversely disposed shoulder or flange 13 provided with an arcuate end face 14, and rectangular in cross section, extending the width of the body. At one side of the flange 13 is an intermediate rectangular shoulder 55 15 also disposed transversely of the body provided with an arcuate end face 16. The shoulder 15 is, however, shorter than the flange; that is to say its end face 16 is located nearer the center of the body than is 60 the face 14. A third or outermost shoulder 17 has its side face coincident with the end face 8 of the body and is disposed transversely of the latter. This shoulder is eccentric to the other two shoulders and has 65 a resultant eccentrically curved, or inclined, or cam end face 18. This face is more remote from the upper extremity of the chaser than is the face 16. The three described shoulders constitute a series of steps receding 70 from the center to the outer end face of the body. Adjacent and below the flange 13 is an intermediate shoulder 20 with an end face 21 similar in all respects to the intermediate shoulder above described. Below 75 the shoulder 20 is a shoulder 22 with its side face coincident with face 9 and eccentric to the shoulders 13 and 20. This shoulder has an eccentrically curved, or inclined, or cam face 23 more remote from the top of 80 the chaser than face 21. The three shoulders 13, 20, and 22 constitute a series of steps receding from the center to the inner end face of the body.

The chaser is initially mounted in the 85 threading tool so that the cam face 23 for an indefinite period receives the thrust from the impelling cam collar. At intervals during this period the chaser is removed and its teeth reground, thus gradually increasing 90 the throat cut at the front end surface of the carrier, as indicated by the broken line 24. This extreme throat cut would render the chaser useless for cutting adjacent any shouldered work, but by virtue of the de- 95 scribed construction the chaser may be withdrawn and returned to place with its front and rear end faces reversed, whereupon cut-

ting upon work adjacent a shoulder may be performed, and the life of the chaser doubled.

I claim:—

- 5 In a chaser, a body provided with a series of teeth upon its lower end, and provided upon its upper end midway its end faces with a transversely disposed arcuate flange, and each side of the flange with an arcuate

intermediate shoulder receding from the flange, and exterior each intermediate shoulder with an end shoulder disposed eccentrically to the flange and to the other shoulders.

In testimony whereof I have affixed my signature.

JOHN J. FLYNN.
